UNITED STATES PATENT OFFICE.

JOHN K. LENCKE, OF KINGSTON, NEW YORK.

MAIL OR EXPRESS CAR.

Application filed July 10, 1928. Serial No. 291,613.

My invention relates to new and useful improvements in express cars, and more particularly to an express car which will be, as far as possible, bandit-proof.

One of the objects of the invention is to provide a car with but a few well-guarded windows, a door at the opposite ends of the car and one centrally located if desired and with the further provision that the interior of the car may be quickly thrown into utter darkness, while the space directly around the car will be flooded with light. Thus the robbers or bandits may be easily discernible, and if close to the car, will be temporarily blinded by high powered lights on the car, while the interior of the car will be dark.

Still another object of the invention is to provide a mail or express car provided with a series of interior and exterior lights and so arranged that one set may be turned off and another set turned on by the pulling of a cord that extends centrally throughout the length of the car. Thus any of the train crew or mail sorters at the first inkling of danger may reach out and grasp the cord, and thus darken the interior of the car and flood the surrounding space with powerful light.

Still another object of the invention is to provide a well-armored car with several entrances, which of course will be well locked and guarded, and to provide an electric lighting system wherein there may be a D. P. D. T. switch so that the moment the lights are turned out in the car, the search lights or high powered light on the exterior of the car will be thrown on.

With these and other objects in view, the invention consists in certain new and novel arrangements and combination of parts as will be hereinafter more fully described and pointed out in the claims.

Referring now to the drawings showing an embodiment of the invention,

Fig. 1 is a side elevation of the improved mail or express car showing a plurality of lights arranged along the side,

Fig. 2 is a diagrammatic view of the car and a diagrammatic view of the wiring system,

Fig. 3 is an end view of the car, and

Fig. 4 is a schematic view of a double pole double throw switch.

Referring now more particularly to the several views, there is shown in Fig. 1 an armored express car 1 and it will be understood that this car may be of any desired or pre-

ferred type as far as the general arrangement is concerned.

On each side of the car, there will be provided the small securely barred windows 2, to provide necessary light in the day time.

There is a door 3 on each side of the car which will be provided with the usual form of bolts or other strong locking mechanism but if desired these doors may be dispensed with and only the doors 4 provided at the opposite ends of the car.

This car on the outside may be lined or covered with a plurality of steel sheets 5 which will be riveted properly and these sheets will divide the outer sides into panel sections formation.

In the alternate upper portions of the panels, the windows 2 are located, while in the panel sections between each window, there will be seen large electric light reflectors 6 that may be of high polished metal. Properly focused within these reflectors will be the electric light globes 7. Likewise two reflectors 8 with their lamps 9 are positioned at each end of the car and at points preferably above the door.

Also extending along the sides are a plurality of small port holes 10, through which machine guns or other fire arms may be projected if the car is attacked by bandits.

Although I have not shown shutters over these port holes, these may be provided if desired.

Referring now to Fig. 2, I have shown schematically a wiring diagram wherein a double pole, double throw switch 11 is shown. The main feed wires 17 connect with the central poles of the switch and also with the source of electric supply, while the wires 12 connect with the lamps 7 that are arranged along the sides of the car and also connect with the lamps 9 that have heretofore been mentioned as fitting within the reflectors at the end of the car.

The other feed wires 13 are shown which are connected with the lamps 14 within the interior of the car.

It is to be noticed that these lamps are wired up in parallel rather than series, so that should one of the lamps be broken, the other would still remain lighted.

Now referring more specifically to the D. P. D. T. switch 11, I have shown schematically in Fig. 4, one manner of arranging this switch, but it is to be of course understood

that any other form of quick acting double pole double throw switch might be utilized.

One way, however, of arranging the switch would be to provide the base 15 of the switch 5 with the common arms 16 to which the main feed wires 17 are connected and the other poles or arms 18 and 19 would be positioned on opposite sides of the swinging arms 16, the wires 12 connected to one set of arms and 10 the wires 13 connected to the other set.

Extending from these arms 16 would be a small eye-bolt or other fastening means 20 to which is to be secured a cord 21, which is adapted to extend throughout the length of 15 the car and be in position to be reached by any of the car crew.

This cord will be preferably centrally located of the car and although I have shown it slightly to one side in Fig. 2, it will be understood that this view is simply schematic and the cord is positioned to one side of the center in this view for the sake of clearness and not to confuse this cord with the wiring system.

25 Small sheaves or pulleys 22 might be provided near the switch and at a slight elevation about the lower arm of the switch, so that the moment the cord 21 is pulled anywhere throughout its length, it will throw the 30 switch arm from one side to the other.

Normally, of course, the switch arm will be so positioned that the lights 14 in the car will be lighted, but at the first inkling of danger, the cord 21 will be pulled to throw the 35 arm 16 to its opposite position and thus light the high powered lights on the exterior of the car.

I have not shown any springs on the switch, 40 but any form of quick acting or snap switch might be used as well as the one shown which is merely for the purpose of illustration.

It might also be mentioned that the high 45 powered lights on the exterior of the car might be so mounted that they could swing about a pivotal axis, so that they could be trained at different points and this is thought so obvious that this is not specifically illustrated, but comes within the purview of the invention.

50 From the foregoing it will be seen that I have provided an express car or car of similar type that will more successfully be able to repel bandits or train-robbers than will the form of express car now in use.

55 It will also be seen that by providing a number of search lights or other high powered lights, that will be arranged along the opposite sides of the car and on the ends thereof; and by providing a switch mechanism, whereby as the lights are turned off in 60 the car, they will be turned on to flood the surrounding territory, much better chance is

provided for protecting the car from the raid of the train robbers, than would otherwise be the case.

65

Again by providing the cord extending, throughout the length of the car and placing it about centrally of the car, and connecting the same with a switch, it will always be in reach of the train crew, or occupants of the 70 express car.

Many slight changes might be made without in any way departing from the spirit and scope of the invention.

Having thus described my invention, what 75 I claim as new and desire to secure by Letters Patent is:

1. An express car or car of similar type, in combination with lights within the car, a plurality of lights positioned around the 80 sides and ends of the car for flooding the surrounding space with light, and means for simultaneously extinguishing the lights within the car and turning on the flood lights.

2. An express car or car of similar type, 85 said car provided with a plurality of port holes, a plurality of lights within the car, a plurality of lights on the sides and ends of the car for flooding the surrounding space outside of the car with light, a double throw 90 90 double pole switch, and means connected with the switch for operating the same, whereby as one set of lights is turned on, the other set of lights is extinguished.

3. An express car or car of similar type 95 having entrances and exits thereto, a plurality of lights around the outside of the car, and a plurality of lights within the car, a switch, means connected with the switch extending throughout the length of the car, 100 whereby said switch may be operated anywhere throughout the length of the car, and the switch so arranged that on turning out the lights within the car, the lights without the car will be instantly lighted.

105 4. In combination with a car body having a wall provided with a port hole, lamps located interiorly and exteriorly of the wall, an open circuit shunted and having a branch connected with each lamp, and a switch adapted to act in common to both branches for closing the branches at different times.

5. In combination with a car body having a wall provided with a port hole, lamps located interiorly and exteriorly of the wall, 115 an open circuit shunted and having a branch connected with each lamp, a switch adapted to act in common to both branches for closing the branches at different times, and a reflector means for intensifying the luminosity 120 of the exteriorly located lamp.

In testimony whereof I affix my signature.

JOHN K. LENCKE.
